VARIABLE RESISTOR

Nelson O. Clark, Winthrop, Mass., assignor to
 Minneapolis-Honeywell Regulator Company,
 Minneapolis, Minn., a corporation of Delaware

Application September 29, 1937, Serial No. 166,374

5 Claims. (Cl. 201—48)

The present invention relates to a variable resistor and more particularly to one which is adapted to be changed in accordance with the value of a condition.

5 An object of the present invention is to provide an improved variable resistance device in which a resistance element of a material which, when placed in a magnetic field, has its resistance varied in accordance with the intensity of 10 said field, is placed in a magnetic field with provision for varying the intensity of the field.

A further object of the present invention is to provide an improved variable resistance device of the type set forth in the previous object in which 15 the means for varying the intensity of the field is a condition responsive one and varies it in accordance with the value of the condition.

A further object of the invention is to provide such a device in which the condition responsive 20 means is a thermo-couple which energizes an electromagnet to produce the magnetic field.

A still further object of the present invention is to provide an arrangement according to the preceding objects in which provision is made for 25 providing flux of high density adjacent the resistance element.

Other objects of the present invention will be apparent from a consideration of the accompanying specification, claims and drawing, of 30 which:

Figure 1 is a sectional view of the improved variable resistance device of the present invention, the section being taken along the line 1—1 of Figure 2, and

35 Figure 2 is a schematic view of a system employing the varying resistance device and in which this device is shown in section, the section being taken along the line 2—2 of Figure 1.

Referring to the drawing, a core member of 40 magnetic material is generally indicated by the reference numeral 10. This core member is cup shaped in form and is provided with a base portion 11, an outer annular wall 12 and a central portion 13. Surrounding the central portion 13 is an electromagnetic coil 14. Also forming a 45 part of the magnetic core is a disc member 15, which is inverted cup shaped in form. The member 15 and the core 10 are both of materials of high magnetic permeability and are joined together at 16 in any suitable manner to insure as high magnetic conductivity across the joint as possible. The upper edge of annular wall 12 is tapered as at 18. Similarly, the lower annular portion of member 15 is tapered as at 20. Located in the space between the tapered edges

of wall 12 and member 15 is a resistance element 21, which resistance element is formed of a material having the property that when it is placed in the magnetic field its resistance is increased in accordance with the intensity of the field. Material which exhibits this property to a great extent is bismuth although some other metals, such as nickel, exhibit this property to a somewhat lesser extent. As more clearly indicated in Figure 2, the resistance element 21 is formed of an insulated wire which is doubled upon itself at 23 so as to form two oppositely wound loops. Due to the doubling back of the wire upon itself, any inductive effect is entirely eliminated. The two ends of the wire are secured to terminal members 25 and 26.

By reason of the bismuth element 21 being located between the tapered edges of the magnetic members 12 and 15, it is subjected to a magnetic field of very high intensity. Due to the extremely high intensity of the field, it is necessary to reduce to a minimum the possibility of leakage around the bismuth element 21. Consequently, the space between member 15 and coil 14 is filled with a material of very low magnetic susceptibility. This material should not only have a low magnetic susceptibility but a very high heat conductivity and a relatively low melting point. The latter two requirements are necessary in view of the low melting point of bismuth making it necessary to have a material of lower melting point than bismuth and at the same time a material which has sufficient heat conductivity to carry away any heat generated in the bismuth conductors. A metal which is particularly desirable for this purpose is ordinary solder consisting of approximately 50 per cent tin and 50 per cent lead. In view of the necessity of conducting away the heat, the space between member 15 and coil 14 is made relatively large to permit a relatively large amount of solder to be passed. This solder has been indicated in the drawing by the reference numeral 28. For the same purposes, that is, preventing any leakage around the element 21 and conducting the heat away from the element, an annular member 29 of triangular cross section is cast on the outside of members 15 and 10. By reason of members 28 and 29, the heat is conducted in both directions from member 21, while at the same time the leakage around this member is held at a very low value so as to intensify the field to which the element 21 is subjected. The solder 28 is supplied through one of two circular openings 30 and 31 extended through member 15. One of these openings

serves for the introduction of the solder and the other for the escape of the air.

A thermo-couple 35 is provided for energizing the electromagnetic coil 14. This thermo-couple 5 consists of inner and outer members 32 and 33 which are of suitable thermo-electric characteristics. Inasmuch as it is desirable to subject the thermo-couple to relatively high temperatures, these elements, particularly the outer one 33, 10 should be of a metal capable of withstanding very high temperatures. It has been found desirable to make the inner metal of "Constantan," an alloy consisting of about 50 per cent nickel and 50 per cent copper and the outer member of stain- 15 less steel. The stainless steel may be of any of the usual alloys known by this name. The two elements 32 and 33 are joined at 34 to provide the hot junction of the thermocouple. At their inner ends the two elements are connected to opposite ends of the winding 14. If the distance between the coil and the hot junction is of appreciable length, it is desirable to terminate the elements 32 and 33 after a relatively short distance and connect these elements with copper elements 20 which have a considerable lower resistance. The elements 32 and 33 are separated from each other by insulation 36.

It will be readily seen that when the hot junction 34 of the thermo-couple 35 is heated, the 30 electromagnetic winding 14 will be energized. This is caused to produce flux in the core 10 and the member 15. In view of the fact that the members 10 and 15 are tapered at their adjacent edges between which the resistance element 21 is located, this resistance element is subjected to flux of extremely high density. The effect 35 of this flux is to change the resistance of element 21. It will be readily apparent that the strength of the magnetic field and consequently the value 40 of resistance 21 will be dependent upon the temperature of the hot junction 34. Accordingly, the arrangement provides a means for varying the value of the resistance in accordance with the value of the controlling temperature. The device has the advantage that it can measure 45 extremely high temperatures since the thermo-couple 35 can be placed in the region of high temperatures and the rest of the structure can be placed outside thereof.

50 While it is obvious that the resistance device just described can be employed for a variety of purposes, such a device is particularly adapted for use in condition control systems. Such an application has been shown in Figure 2 wherein 55 the device in question is used as the controlling element of a proportioning system and is used to control the position of a valve controlling the flow of fuel to a burner, or other similar heating device. In this figure, the valve has been generally indicated by the reference numeral 40. This valve is provided with a valve stem 41. The valve 40 controls the flow of fuel through a fuel line 42 leading to a burner, or other similar heating device (not shown). A motor generally indicated 60 by the reference numeral 45 controls the position of valve 40. The motor 45 is of the condenser induction type and comprises a rotor 46 and a pair of field windings 47 and 48. Associated with the field windings is a condenser 49. The rotor 70 46 is connected to a reduction gear train 50 and drives, through the reduction gear train 50, a shaft 51. Shaft 51 carries a crank disc 52 which is connected through a link 53 with the valve stem 41. The condenser 49 is adapted to be connected 75 in series with either one or the other of

the two field windings 47 and 48. When the condenser is connected in series with one of the field windings, the rotor rotates in one direction, and when connected in series with the other field winding, it rotates in the other direction.

A relay generally indicated by the reference numeral 55 controls the energization of the motor and the connection of the condenser 49 to the field windings 47 and 48. The relay consists of a pair of field coils 56 and 57 which are connected 10 together at one end. Associated with the coils 56 and 57 is an armature member 58 which is operatively connected through a suitable connecting member 59 with a switch blade 60. The switch blade 60 is adapted to engage either of 15 two contacts 61 and 62. When relay coil 56 is more highly energized than relay coil 57, armature 58 is drawn to the left moving the switch blade 60 into engagement with contact 61. When, on the other hand, relay coil 57 is more 20 highly energized than relay coil 56, the opposite movement of armature 58 takes place causing switch blade 60 to be moved into engagement with contact 62.

A step-down transformer is employed for supplying low voltage power for operation of this system. This step-down transformer is generally indicated by the reference numeral 65 and comprises a low voltage secondary 66 and a line voltage primary 67. The line voltage primary 67 30 is connected to line wires 69 and 70 leading to any suitable source of power (not shown). The low voltage secondary 66 is connected to conductors 71, 72, 73, and 74 to the opposite terminals of the relay coils 56 and 57. Accordingly, it will 35 be seen that the relay coils 56 and 57 are connected in series across the secondary. The terminal 26 of the two terminals 25 and 26 of the variable resistance device previously described is connected through a conductor 76 with the outer 40 terminal of relay coil 56. The other terminal 25 of the variable resistance device is connected through conductors 77 and 78 to the movable contact 79 of a rheostat 80, the fixed resistance 81 of which is connected through conductors 82 45 and 83 to the junction of relay coils 56 and 57. It will accordingly be apparent that the variable resistance element 21 is connected across the relay coil 56 in series with the rheostat 80. For any fixed adjustment of the rheostat 80, the voltage impressed across the relay coil 56 is controlled in part by the value of resistance 21.

A second rheostat 85 is provided for the purpose of controlling the energization of relay coil 57. This rheostat 85 comprises a resistance 86 55 and a movable contact 87. The resistance 86 is connected directly to the left-hand terminal of relay coil 57 and the movable contact 87 is connected through conductors 88 and 78 with the movable contact 79 of rheostat 80. It will accordingly be seen that rheostat 85 is connected across relay coil 57 in series with the rheostat 80. The rheostat 80 is accordingly in circuit with both the resistance 21 and the rheostat 85. The rheostat 85 is used for adjusting the temperature setting of the variable resistance including resistance element 21. It will be apparent that the point at which the energization of resistance elements 56 and 57 is balanced is determined by the setting of the rheostat 85. By moving the 70 slider 87 to the right, it is necessary to have a considerably higher temperature before the resistance element 21 has a resistance equal to that of the rheostat 85. Similarly, moving the slider 87 to the left decreases the value of the tempera- 75

ture to which the thermo-couple 35 must be subjected to balance the energization of relay coils 56 and 57.

The rheostat 80 is for the purpose of varying the sensitivity of the apparatus. It will be apparent that the resistance value of this rheostat determines the effect that a given change in the resistance value of resistance 21 will have upon the relative energization of relay coils 56 and 57.

For a given setting of rheostats 80 and 85, it will be apparent that an increase in the temperature to which thermo-couple 35 is subjected will cause relay coil 56 to have a higher voltage impressed across the same and consequently to become more highly energized than relay coil 57. Similarly, a decrease in the temperature to which thermo-couple 35 is subjected will cause a decrease in the energization of relay coil 56.

A potentiometer 90 is used for also controlling the relative energization of relay coils 56 and 57. This potentiometer comprises a resistance element 91 and a movable contact arm 92. The movable contact arm 92 is secured to shaft 51 so that the same is actuated whenever the position of the valve is changed. The opposite terminals of resistance 91 are connected through conductors 94 and 72 on the one hand and 95 and 74 on the other hand to the opposite terminals of relay coils 56 and 57. The arm 92 is connected through conductors 96 and 83 with the junction of relay coils 56 and 57. It will be readily apparent that the potentiometer 90 acts as a voltage divider and that the position of contact arm 92 controls the relative energizations of relay coils 56 and 57. Thus, any movement of contact arm 92 to the right tends to increase the energization of relay coil 56 and decrease that of relay coil 57. Conversely, when the arm 92 is moved to the left, the energization of relay coil 57 is increased and that of relay coil 56 is decreased. The potentiometer 90 is used as a rebalancing potentiometer to terminate movement of the motor after the same has moved a distance corresponding to the temperature change producing the initial unbalance in the energization of relay coils 56 and 57. This operation will be more apparent from a description of the operation of the system as a whole.

50

Operation of the system

The various elements of the system are shown in the position which they occupy when the temperature to which thermo-couple 35 is subjected is approximately at the desired value. Let it now be assumed that the temperature to which thermo-couple 35 is subjected decreases in value. This will cause a decrease in the flux generated by the electromagnetic coil 14 and consequently a decrease in the resistance value of resistance element 21. The result is that the energization of relay coil 56 will be decreased relative to that of relay coil 57 causing armature 58 to move to the right and move switch blade 60 into engagement with contact 62. When this takes place, the following circuit is established to the field winding 47: from line wire 69 through conductor 98, switch arm 60, contact 62, conductors 99 and 100, field winding 47, and conductor 101 to the other line wire 70. At the same time, a circuit is established to the other field winding 48 as follows: from line wire 69 through conductor 98, switch arm 60, contact 62, conductors 99 and 103, condenser 49, conductors 104 and 105, field winding 48, and conductor 101 to the other line wire

70. It will be noted that field winding 47 is directly connected across the line wires whereas field winding 48 is connected in series with condenser 49. The result is that the current through field winding 48 leads that through field winding 47 so as to produce a rotating field which causes rotation of rotor 46. The rotation of rotor 46 causes a clockwise movement of crank disc 52 to move valve 40 towards open position. This admits more fuel to the burner, or other fuel consuming device, to raise the temperature to which thermo-couple 35 is subjected.

At the same time that the rotation of crank disc 52 is being effected, contact arm 92 is rotated towards the right on resistance 91. As previously explained, movement of contact arm 92 to the right on resistance 91 tends to increase the energization of relay coil 56 and decrease that of relay coil 57. It will be obvious that this action is opposite to that produced by the decrease in the temperature to which thermo-couple 35 is subjected so that after movement of contact arm 92 has continued for a certain time, energization of relay coils 56 and 57 will again be balanced so that armature 58 moves the switch blade 60 away from contact 62 into the neutral position shown in the drawing. This will terminate operation of the motor, the motor having moved the valve a distance corresponding to the temperature change causing the original unbalance in energization of relay coils 56 and 57.

Let it be assumed now that the additional fuel supplied by valve 40 causes the temperature adjacent thermo-couple 35 to rise again, the increase in temperature to which thermo-couple 35 is subjected will cause the resistance value of resistance 21 to correspondingly increase. The effect of this is to increase the energization of relay coil 56 and to unbalance the relay 55 in the opposite direction causing switch blade 60 to be moved into engagement with contact 61. When this occurs, the following circuit is established to relay coil 48: from the line wire 69 through conductor 98, switch blade 60, contact 61, conductors 107 and 105, field winding 48, and conductor 101 to the other line wire 70. At the same time, a circuit is established to field winding 47 as follows: from line wire 69 through conductor 98, switch blade 60, contact 61, conductors 107 and 104, condenser 49, conductors 103 and 100, field winding 47, and conductor 101 to the other line wire 70. It will be noted that in the new position of switch blade 60, field winding 48 is directly connected across the source of power whereas field winding 47 is connected in series with condenser 49. The current through field winding 47 accordingly now leads that through field winding 48 so as to cause rotation of rotor 46 in a direction opposite to that which previously occurred. This opposite rotation of rotor 46 will cause a counter-clockwise rotation of shaft 51 and consequently a counter-clockwise movement of crank disc 52. This movement of crank disc 52 is effective to move valve 40 towards closed position reducing the amount of fuel supplied to the burner, or other heating device.

At the same time that crank disc 52 is rotated in a counter-clockwise direction, the contact arm 92 is moved to the left on resistance 91. This has as its effect the increase in the energization of relay coil 57 and a decrease in the energization of relay coil 56. It will be apparent that after a limited amount of movement of the shaft 51, the energization of relay coils 56 and 57 will again be rebalanced causing switch blade 60 to

75

move to the position shown in the drawing, in which position the operation of the motor is terminated.

It will be apparent from the foregoing description that the position of valve 40 is controlled at all times by the temperature to which thermo-couple 35 is subjected. The use of the variable resistance device of the present invention eliminates any necessity for movable contact members on a condition responsive device. This is particularly desirable in the case of a condition responsive variable resistance since the power which a condition responsive element is capable of delivering without too great sluggishness or inaccuracy is extremely limited. In a system such as that shown in Figure 2, it is possible to employ movable contact members in the rebalancing means since this is driven by a relatively powerful motor. However, it is not possible in the main control resistance for the reason pointed out above. The effect, therefore, of the substitution of the variable resistance means of the present invention is to greatly increase the accuracy of the system as a whole.

While I have shown the variable resistance device of the present invention as applied to a proportioning system for the control of a temperature controlling valve, it is to be understood that the same is adapted for numerous other applications. In general while I have shown a specific embodiment of my invention, it is to be understood that this is for purposes of illustration only and that the invention is to be limited only by the scope of the appended claims.

I claim as my invention:

1. A variable resistance arrangement comprising a core of magnetic material including a central portion and an outer cylindrical shell forming with said central portion a closed magnetic path except for a narrow annular gap, an electromagnetic coil within said outer shell and surrounding said central portion, a circular resistance element in said gap longitudinally thereof and of a material which when placed in a magnetic field has its resistance varied in accordance with the intensity of the field, and means for variably energizing said coil.

2. A variable resistance arrangement including an electromagnetic coil, a core of magnetic material on which said coil is disposed, said core forming a completely closed magnetic path with

the exception of a narrow annular gap, a resistance element in said gap and of a material which when placed in a magnetic field has its resistance varied in accordance with the intensity of the field, material of high heat conductivity and low magnetic susceptibility disposed on each side of said gap and extending over the adjacent magnetic material, and means for variably energizing said coil.

3. A variable resistance arrangement comprising an electromagnetic coil, a core of magnetic material on which said coil is disposed, said core forming a completely closed magnetic path with the exception of a narrow annular gap adjacent which the core is tapered to concentrate the flux, a resistance element in said gap and of a material which when placed in a magnetic field has its resistance varied in accordance with the intensity of the field, metal of high heat conductivity and low magnetic susceptibility disposed on each side of said gap and extending over the tapered portions of the magnetic core, and means for variably energizing said coil.

4. A variable resistance arrangement including an electromagnetic coil, a core of magnetic material on which said coil is disposed, said core forming a completely closed magnetic path with the exception of a narrow elongated gap, a resistance element in said gap longitudinally thereof and of a material which when placed in a magnetic field has its resistance varied in accordance with the intensity of the field, material of high heat conductivity and low magnetic susceptibility disposed on each side of said gap closely adjacent said element, and means for variably energizing said coil.

5. A variable resistance arrangement including an electromagnetic coil, a core of magnetic material on which said coil is disposed, said core forming a completely closed magnetic path with the exception of a narrow elongated gap, a resistance element in said gap longitudinally thereof and of a material which when placed in a magnetic field has its resistance varied in accordance with the intensity of the field, material of high heat conductivity and low magnetic susceptibility disposed on each side of said gap and extending over the adjacent magnetic material, and means for variably energizing said coil.

NELSON O. CLARK.
